(57) CLAIM

The ornamental design for a sport pen and pad set, as shown and described.

DESCRIPTION

FIG. 1 is a top planar view of a sport pen and pad set showing my new design.

FIG. 2 is a bottom planar view of the sport pen and pad set.

FIG. 3 is a side view of the sport pen and pad set.

FIG. 4 is a rear view of the sport pen and pad set.

FIG. 5 is a frontal view of the sport pen and pad set; and, FIG. 6 is a perspective view of the sport pen and pad set in an exploded condition.

The indicia depicted by means of broken lines in FIGS. 1 and 6 has been shown for illustrative purposes only and forms no part of the claimed design.
